UNITED STATES PATENT OFFICE

1,966,483

WOOD HEEL ATTACHING MACHINE

Arthur J. Brauer and Frederick P. Wagner,
St. Louis, Mo.

Application August 24, 1931, Serial No. 558,916

5 Claims. (Cl. 12—42)

This invention relates generally to machines for attaching wooden heels to shoes, and particularly to such a machine in which the shoe is supported with the bottom up during the course of operation.

In the manufacture of shoes such as ladies' shoes which are provided generally with wood heels, it is customary to cement the heel in position upon the heel seat of the shoe and to insert a temporary fastening device, such as for instance a screw for clamping the cemented heel firmly against the lasted shoe while the cement is setting. Subsequently, after the cement has set, the temporary fastening means has been withdrawn and the shoe delasted, it is the usual practice to nail the heels in position. In view of the fact that it is of considerable importance in the manufacture of high grade shoes that the wood heel be accurately and properly aligned with the sole as well as the upper, it is advantageous that the operator who temporarily attaches the heels to the shoe be able to fully view the heel and lasted shoe while the heel is being placed thereupon and clamped. It has been heretofore the practice generally that a shoe be supported with the bottom thereof down as the temporary securing device is being applied to the heel and accordingly in view of the fact that the operator could not properly view the work, the heels have, in many instances, been secured in position without proper alignment so that the beauty which the shoe might otherwise have is not present.

An object of this invention, generally stated is to provide a wood heel attaching machine having the parts constructed and arranged to support the shoe with the bottom thereof extending upwardly during the application of the usual temporary securing device.

Another object of this invention is to provide a wood heel attaching machine having a shoe support mounted for movement relative to the usual clamp in order to facilitate positioning of the shoe and heel.

A further object of this invention is to provide a machine of the kind described with a device for accurately aligning a lasted shoe upon a support.

Another object of this invention is to provide a wood heel attaching machine in which the device for driving the temporary securing device is accurately guided by the frame of the machine.

Other objects will become apparent to those skilled in the art when the following description

is read in connection with the accompanying drawing in which:

Figure 1 is a view in side elevation of a wood heel attaching machine constructed in accordance with this invention.

Figure 2 is a view in front elevation of the movable shoe support employed on the wood heel attaching machine illustrated in Figure 1.

Figure 3 is a perspective view of a heel engaging member.

Generally stated, in accordance with this invention, the operative parts of a wood heel attaching machine are so constructed and arranged that the shoe being operated upon is supported with its bottom up in order that it may be clearly viewed by the operator and accordingly with the shoe so supported means is provided for inserting or driving the usual temporary securing device into the heel and through a hole in the last upwardly into the heel while at the same time suitable clamping means is provided for mounting the wood heel to be secured in position upon a lasted shoe.

Referring now particularly to the drawing, a wood heel attaching machine constructed in accordance with the present invention is shown and in the embodiment illustrated, the temporary fastener driving device shown is of a type particularly adaptable for use in connection with a last provided with a temporary securing means disclosed in U.S. Patent No. 1,898,288, patented February 21, 1933, in which a last is provided with a permanent assembly including a securing device such as for instance a screw, but it

will be distinctly understood that the machine of the present invention is not limited to use in connection with such a securing device, but may be advantageously employed in applying the ordinary screws which are usually employed. The machine illustrated in Figure 1 is provided with a suitable frame 1 which may be in the nature of a pedestal mounted upon a suitable base 2 and carrying at its upper end a guiding arm 3 having cylindrical portions 4 adapted to receive in

slidable relation thereto a bar 5. The bar 5 extends downwardly within the pedestal 1 and may be provided with a suitable cushioning device as a spring 6 having one end thereof seated against an abutment 7 on the interior of the pedestal

1 and the other end thereof engaging a suitable abutment as a collar 8 mounted upon the bar 5. With such an arrangement, it is apparent that the spring 6 will tend to force the bar 5 upwardly relative to the pedestal 1, until the weight of the bar and its associated parts just

- balance the force of the spring 6 at which time the parts will come to rest. Pivots attached to the lower end of the bar is a link 9 having one end thereof pivots attached to a treadle 10 pivotally supported by a suitable lug 11 on the base plate 2. The treadle 10 preferably extends outwardly from the frame of the machine to a convenient position for operation as illustrated in Figure 1. At its upper end, the bar 5 carries an arm 12 which is provided at its outer end with a suitable guideway 13 adapted to receive in slideable relation thereto a bar 14. Suitable adjusting means is preferably provided whereby the position of the bar 14 may be varied within the guide-way 13. For instance, the guideway 13 may be of a split construction and provided with a suitable adjusting screw as 15 for tightening the same in order to maintain the bar 14 in fixed position therewithin. Pivotally mounted upon the lower end of the bar 14 is a heel engaging member 16 having an abutment 17 adapted to engage the top lift of a wood heel and suitable abutments 18 which are preferably of non-abrasive material adapted to engage the face of a heel.
- Extending outwardly from the pedestal 1 is a suitable frame part or table 19 which may be integrally formed with the pedestal 1 so that a continuous frame structure is provided. Suitable re-enforcing ribs as 20 may be provided for strengthening the frame thus formed. Mounted upon the upper surface of the table 19 is a shoe support 21 provided at the top thereof with a post 22 adapted to enter the usual thimble such as 23 of the last 24. In accordance with the present invention, the shoe support 21 is connected to the table 19 through a hinge connection 25 so that the support 21 is tiltable, as indicated by the arrow in Figure 2, about a shaft 26 as an axis. With such an arrangement, it is apparent that an operator may tilt the shoe support 21 to the side, as illustrated by the arrow in Figure 2, for a distance sufficient to permit a lasted shoe to be readily placed thereupon and while thus tilted, the operator may if desired position the wooden heel to be applied to the shoe in proper alignment. With the lasted shoe and its corresponding heel thus positioned, the support 21 may be returned to the position illustrated in Figure 2 where, it will be understood, that the shoe carried thereby with its corresponding heel as 27 will be positioned for cooperation with the heel engaging member 16. When the operator is ready to proceed with applying the temporary fastening device, he may then step upon the treadle 10, which will cause the bar 5 to be moved downwardly and with it the arm 12, as well as the heel engaging member 16. It is apparent, therefore, that the apparatus, including the bar 5, the treadle 10, the arm 12 and the heel engaging member 16, cooperate as a clamping mechanism to clamp the heel upon a shoe which is held in stationary position with reference to the frame of the machine.
- The shoe support 21 is in accordance with the present invention provided with a device adapted to cooperate with a last thereupon to align the shoe upon the support. Such an aligning device may be in the nature of a plate 28 hingedly connected to a support as through a shaft 29 and preferably provided with a stiff leaf spring 30 having one end thereof secured to the support 21 and the other end thereof in engagement with the plate 28 tending to force the same in a clockwise direction as seen in Figure 1. As is

clearly illustrated in Figures 1 and 2 the plate 28 is of such length that the end thereof extends upwardly beyond the end of the support 21 and as shown in Figure 1, the plate 28 is so disposed as to engage and cooperate with the inclined portion 31 of the last adjacent the cone. With such an arrangement it is apparent that if the spring 30 be of sufficient stiffness, the force thereof acting through plate 28 will be effective to cause the inclined portion 31 to become accurately aligned with the plate 28 in view of the fact that the last is rotatable about the post 22. It is apparent, therefore, that with such a positioning device as the plate 28 the shoe will be accurately positioned upon the support before being moved into position for cooperation with the clamping device and other cooperating parts to be now described.

In order to drive the temporary securing device, which is usually employed for attaching wood heels, into position suitable driving mechanism is provided. Such driving mechanism may comprise a suitable chuck as 32 adapted to receive a tool 33 for cooperation with the temporary securing device or fastener 34, but it may be pointed out that in lieu of the tool 33 and fastener 34, an ordinary heel attaching screw may be employed in which case such a tool as 33 will be unnecessary and it will be further understood that the head of the chuck 32 may be so formed as to receive any suitable or desired head which may be provided upon the usual securing device or fastener. Attached to the chuck 32 for driving the same is a shaft 35 extending through an aperture 36 in the table portion 19 of the frame so as to guide the same in its movement axially thereof as the chuck 32 is being moved toward a shoe in order to force the fastener into position. It may be pointed out that the shaft 35 is preferably connected through a yieldable driving mechanism which may be of any desired type in order to prevent the transmission of a driving force in excess of the predetermined value to the tool 33. The driving force for the shaft 35 may be transmitted through a suitable flexible shaft as 37 from a gear or chain drive mounted in a housing 38 and driven by a motor 39. It will be understood that a suitable driving mechanism such as for instance a worm and a worm gear may be mounted in a housing 40 for transmitting the driving force from the flexible shaft 37 to the shaft 35.

A lever 41 is pivoted through a suitable lug as 42 to the frame of the machine and is attached through a link 43 to the side of the housing 40. A spring such as 44 may be provided for supporting the housing 40 and its adjunct parts and a bifurcated member as 45 having one prong thereof extending on each side of the shaft 37 may be provided for a guiding mechanism in its vertical travel. It is apparent, therefore, that after an operator has positioned the shoe and its corresponding heel upon the support 41 and has stepped upon the treadle 10 in order to clamp the heel in position upon the shoe, he may then grasp the lever 41 and lift the same upwardly in order to move the tool 33 into position for cooperative engagement with the temporary securing device or fastener 34. The operator may continue to lift upwardly upon the lever 41 until the fastener 34 is driven home at which time the yieldable connection for the shaft 35 will begin to slip, thus indicating to the operator that the fastener is driven home, where-

upon the lever 41 may be released and the parts will drop into the position shown in Figure 1, being cushioned in their downward movement by a spring 44. At the same time, the operator 5 may release the treadle 10 whereupon the clamping parts will be moved by the spring 6 upwardly thus releasing the pressure upon the heel 27.

From the foregoing description it is believed that the operation of a machine constructed in 10 accordance with the present invention will be apparent and it will be seen that a wood heel attaching machine is provided in which the shoe to be operated upon is supported in such a position that an unobstructed view of the heel and 15 the heel seat may be had by the operator while the parts are being placed in position. It is apparent that many modifications of the machine hereinbefore described and illustrated in the accompanying drawing will present themselves to those skilled in the art without departing from the spirit of this invention. It is to 20 be distinctly understood, therefore, that the invention is not limited to the specific details which have been hereinbefore set forth and that 25 such modifications and the use of such individual features and sub-combinations of features as do not depart from the spirit of this invention are, although not specifically described herein, contemplated by and within the scope of 30 the appended claims.

Having thus described the invention, what is claimed is:

1. A machine for securing heels to shoes on 35 lasts having fastener receiving recesses therein, comprising a frame, a last support arranged to position a last relative to the frame, and fastener driving means guided by said frame for movement in substantial alinement with the fastener

receiving recess of a last positioned on said support.

2. A machine for securing heels to shoes on lasts having fastener receiving recesses therein, comprising a frame, a last support arranged to position a last relative to the frame, fastener driving means guided by said frame for movement in substantial alinement with the fastener receiving recess of a last positioned on said support, and clamping means disposed to engage the heel of a shoe on said support. 85

3. A machine for securing heels to shoes on lasts having fastener receiving recesses therein, comprising means engageable with a last part for supporting a last with the recess down, and fastener driving means normally disposed outside of the recess when the last is in position on said supporting means and guided for up and down movement in substantial alinement with the recess of a last. 90

4. A machine for securing heels to shoes on lasts having a fastener mounted therein and extensible therefrom to engage a heel, fastener driving means movable into engagement with said fastener, and last supporting means movable to position said fastener in cooperative alinement with said driving means. 100

5. A machine for securing heels to shoes on lasts having a fastener mounted therein and extensible therefrom to engage a heel, comprising, a frame, a last support on the frame arranged to position the last, and fastener driving means having a part mounted in the frame in substantial alinement with the fastener of a last positioned on said support and movable into engagement with the fastener. 105
